UNITED STATES PATENT OFFICE

168,864

NAME PLATE

Seymour Schneider, Astoria, N. Y.

Application May 22, 1952, Serial No. 19,823

Term of patent 3½ years

(Cl. D1—7)

To all whom it may concern:

Be it known that I, Seymour Schneider, a citizen of the United States, residing at Astoria, L. I., N. Y., have invented a new, original, and ornamental Design for a Name Plate, of which the following is a specification, reference being had to the accompanying drawing, forming part thereof, in which—

Fig. 2 is an end view; and,

Fig. 3 is a bottom plan view.

I claim:

The ornamental design for a name plate, as shown.

SEYMOUR SCHNEIDER.
